UNITED STATES PATENT OFFICE.

PETER W. ANDERSON, OF CHICAGO, ILLINOIS.

BUILDING.

SPECIFICATION forming part of Letters Patent No. 411,516, dated September 24, 1889.

Application filed April 15, 1889. Serial No. 307,237. (No model.)

To all whom it may concern:

Be it known that I, PETER W. ANDERSON, a citizen of the United States, and a resident of Chicago, in the county of Cook and State of Illinois, have invented new and useful Improvements in Buildings, of which the following is a specification, reference being had to the annexed drawings, (two sheets,) in which—

Figure I, Sheet 1, is a one-fourth of a plan 10 view of a building constructed on my plan; Fig. II, a vertical section on Fig. I, dotted lines Z, showing the stairs in elevation and a portion of the roof in section; Fig. III, a horizontal section of Figs. I and II on line w, Fig. 15 II, with stairs omitted; Figs. IV and V, plan views of the top portions of the towers above; Fig. VI, Sheet 2, a section and elevation of the mason-work and frame-work of the plan, Fig. VII, Sheet 2, on line a, with the stairs 20 and circular walls omitted, showing also half of tower; Fig. VIII, a horizontal section of Fig. VI on line b; Fig. VIII, a detail of the frame-work in cathedral construction.

The building may be constructed with any 25 number of sides desired, or it may be round. It can also be built to cover any-sized lot, from twenty to six hundred feet in length and a corresponding breadth. It is particularly adapted for public buildings and other large 30 buildings—such as office-buildings, churches, halls, hotels, and apartment-buildings—being so constructed that there is no space or light lost by columns or other supports, which are deemed necessary as buildings are now constructed. The base of the dome or tower is 35 supported by suitable truss-work bearing at its outer connections on the inner portions of V-shaped walls of sufficient length to inclose compartments exterior to the main compartment. On my plan a building one hundred and fifty feet in diameter is capable of supporting a tower or spire seventy-five feet above the center dome, and on a building three hundred feet wide it is capable of supporting a 40 tower or spire one hundred and fifty feet above such dome. The interspaces of the V-shaped abutments can be built in with circular mason-work and on the tops thereof towers can be erected, and inside thereof stairs can be 45 constructed leading to stairs in the main tower or spire, or the space within the towers 50

can be used for vaults or other purposes. If the structure is for an office-building, the exterior towers, or a portion of them, can be used for elevators and the admission of light 55 to the interior of the building. If the structure is for a church, the rostrum can be in the center of the main compartment and the speaker can be seen unobstructed by columns or other supports. The rostrum, however, 60 may be located at any place within the halls and be in view of all persons present.

The gist of the invention consists in such a construction that the walls of the exterior rooms serve as abutments for the support of 65 the roof or dome, in contradistinction to outside pilasters and interior columns or supports. If pilasters or columns are employed, they will be simply for ornament, and not for any necessary support. 70

Fig. II, being an elevation of Fig. I on line Z, shows the outside wall c of the circular portion D, in which the stairs S may be erected, and an inner compartment E, which is below the inner small tower and below the tower-stairs T. 75 The walls at the sides of the circular portions D E are to be constructed of the best mason-work, which may support towers F G above, or they may extend only to form a finish at the eaves or corners of the structure; but 80 where stairs are to run to a central tower the towers will have to be extended properly for that purpose. The inner portions of the walls A engage the lower end portions of the truss-beams K, one of which is shown at Fig. 85 VII. A modification of truss is shown at e e f, and is forked, that windows d between walls A A may be employed to light inner compartments; and to this end the inner ends of the walls should be united with a strong cross- 90 wall.

B represents the walls connecting with the walls A A, and they may be constructed to have any desired number and style of window, and at Fig. VII windows may be placed in the 95 walls A A.

Inside of the walls A A B, Fig. VII, may be laid off compartments, the ground plan of which is shown by line g g h and j k. The walls of such compartments may be fixtures 100 or composed of folding or sliding doors.

At Fig. III the rectangular spaces between

walls A A B may be inclosed at C for vaults, library-rooms, elevators, or lobby-rooms, as may be desired.

For large structures the apartments inside 5 of walls A A B will be ample for the above-mentioned purposes, and for churches they will be large enough for class-rooms, lecture-rooms, school - rooms, and organ - room and choir, and, as shown at 2, 3, and 4, Fig. VI, a 10 series of balconies can be constructed within the walls A A B, that all the room of the structure may be utilized as an audience-room, and columns *n* may be erected between the balconies to give a neat appearance. *m* 15 represents both the roof and ceiling over balcony 4, Fig. VI.

The workmanship to put in practice my invention must be of the best kind and the material must be the best, and the foundations 20 must be constructed so as not to settle.

For small buildings, wood may be used for beams, girders, and rafters, but for medium and large buildings the principal frame-work should be of iron or steel.

25 The roof will of necessity have as many sides U V as the building has, and it may be ornamented by small towers, pinnacles, and have constructed therein ample skylights and ventilators, as is the custom in modern buildings.

H' represents the cornice extending around the building and of a height to *I*, Fig. VI.

30 *G'* represents the highest point of the dome, and the frame surrounding the same, as shown at Fig. I, has the same number of sides as the building supporting this portion of the dome, are supported by main trusses *K* extending from the inner portions of the walls A A to the frame *h'*.

40 *M* is a chord extending from each truss *K* to the exterior of the building, and having an outer support on the wall and roof portion *m*, Fig. VI.

G represents the main tower, and its main support are struts *L*, having footings just 45 above the lower ends of the trusses *K*.

N shows one of the secondary struts, and *P* and *Q* are posts or binding-braces, one of which is at the corner of each octagon.

At Fig. VIII is a detail in plan of a part of 50 the horizontal ties to the dome, which needs no description.

55 *R* is one-half of the base of the central tower, it being united with the frame-work below, in the ordinary manner of the most substantial structures.

I claim as new and desire to secure by Letters Patent—

1. A building constructed with exterior apartment, the walls of which extend in from 60 the exterior walls and form V-shaped spaces or recesses between the exterior walls, in combination with a truss-support for the roof, having its footings on the inner ends of such V-shaped walls, and a dome *G'*, uniting the 65 upper ends of such truss-support, as and for the purpose specified.

2. A building constructed with V-shaped recesses in its interior walls, and apartments formed between such V-shaped walls, and a 70 truss-dome and spire supported upon the inner ends of the V-shaped walls, as and for the purpose specified.

3. A building constructed with V-shaped recesses in its interior walls, and compartments formed between such V-shaped walls, and a truss-dome and spire supported on the inner ends of the V-shaped walls, and the 75 said recessed walls supported by mason-work, having two circular openings, as and for the 80 purpose specified.

PETER W. ANDERSON.
